UNITED STATES PATENT OFFICE.

BRUCE CLARK WHITE, OF NEW YORK, N. Y., ASSIGNOR TO FEDERAL ELECTRIC COMPANY, OF CHICAGO, ILLINOIS, A CORPORATION OF ILLINOIS.

GEARING FOR WASHING MACHINES.

Application filed May 1, 1920. Serial No. 378,072.

To all whom it may concern:

Be it known that I, BRUCE CLARK WHITE, a citizen of the United States, and a resident of New York city, in the county of New York and State of New York, have invented certain new and useful Improvements in Gearing for Washing Machines; and I do hereby declare that the following is a full, clear, and exact description thereof, reference being 10 had to the accompanying drawings, and to the letters of reference marked thereon, which form a part of this specification.

This invention relates to an improvement in gearing for washing machines and consists of the matters hereinafter described and more particularly pointed out in the appended claims.

My invention relates to a gearing for washing machines in which a rotating crank 20 is connected to an oscillatory operating arm or to an operating pin designed to impart a rotary, oscillatory movement to the operated member, as the drum or cylinder, of a washing machine.

25 When a crank is connected by a pitman to drive an oscillating arm or to drive a pin designed to travel in an arcuate path, the rate of movement of the oscillating member will be relatively slower at successive points 30 in its path when moving in a direction away from the position of the crank orbit than at the corresponding points in its path, beginning from the other end of said path, when the oscillating member is moving towards said crank orbit. This is due to the fact, capable of ready demonstration, that in the movement of the oscillating member away from the crank orbit, its rate of movement is in proportion to the arithmetical 35 difference between the versed sines of the angles of the crank and of the pitman, whereas on the return movement of the oscillating member toward the crank orbit, its rate of movement is in proportion to the arithmetical 40 sum of the versed sines of said angles. The movement of the oscillating member thus lacks uniformity of acceleration in the two directions and while slow enough at that end of its path of movement 45 nearest to the crank orbit, the movement is too fast and has too sudden and rapid acceleration upon the reverse, at the other end of its path of movement.

My invention is designed to correct this

evil and to produce a substantially uniform 55 slowing down and a substantially uniform, gradually increasing speed after reversal, at both ends of the path of movement of the oscillating member, and of the cylinder or drum actuated thereby.

60 Thus one of the objects of the invention is to provide a gearing which is adapted to so translate the rotary movement of a crank arm into an oscillatory movement of an operating arm or of a pin moving in an arcuate path and of the oscillatory washing machine member actuated thereby, that the oscillatory movement shall be uniformly slow at both limits of its oscillation and shall have a substantially uniform rate of acceleration in both directions to and from the more rapid rate of movement intermediate 70 said limits of oscillation. This and other objects and advantages of the invention will be more particularly pointed out as I proceed with my specification.

75 In the drawings:—

Figure 1 represents a side elevation of a washing machine having an oscillatory cylinder and provided with my improved 80 gearing.

Figures 2 and 3 are detail views of the 85 gearing on an enlarged scale, representing the parts of the gearing in different positions.

Figures 4 and 5 are diagrammatic views which will be more particularly described in the specification.

90 Referring to that embodiment of the invention illustrated in the drawings:—10 indicates the body of a washing machine, which is of any suitable construction. It includes a tub 11 to contain the water for washing the clothes, and an oscillatory cylinder 12, which is the receptacle for the 95 clothes to be washed. 13 indicates the usual wringer mounted on the tub.

100 The cylinder or receptacle 12 is mounted in the tub in any convenient manner so as to be capable of an oscillatory movement of a predetermined amplitude. The gearing for imparting movement is all mounted on a bar or frame 14, which is attached to the upright legs 15—15 at one end of the tub. The gearing is preferably enclosed in a gear 105 case 16, provided between the legs 15—15 and the adjacent end of the tub 11,—a door 17 (shown in dotted lines in Fig. 1) hinged

to one leg of the tub body, forming a closure for the gear case.

The oscillatory movement is imparted to the tub by means of an operating arm 18, fixed to a stud shaft 19, which has rotative bearing in a standard 14^a rising from the bar 14. Said stud shaft has its axis coincident with the axis of the oscillatory receptacle 12, and is capable of operative connection therewith in a familiar way not necessary to be described herein.

At one side of the operating arm 18, and as illustrated, somewhat below the same, is located a worm gear 20, which is suitably mounted on the bar or frame 14. Said worm gear is in a plane at right angles to the axis of the stud shaft 19 and is driven by a horizontal worm 21 on a shaft 22, which is in line with and is operatively connected to a shaft 23 of a motor 24. The motor 24 is attached to and supported by the bar or frame 14. A friction coupling mechanism 25, is preferably interposed between the shaft 22 and the motor shaft 23, in order to relieve the motor shaft in case the gearing or the parts driven thereby become obstructed or otherwise prevented from operation, so as to put too great a load on the motor.

30 The wringer 13 is driven by an upright shaft 26, which is connected by a worm gear 27, at its bottom end to the worm 21.

28 indicates a crank pin on the worm gear, and 29 indicates the pitman which is designed to drive the operating arm 18. A radius arm 30 is pivoted on the standard 14^a to a horizontal pin 31. Said pin, as illustrated, is positioned below and a little to the right of the stud shaft 19. The end of the radius arm 30 is pivotally connected by a pin 32, to the pitman 29. A link 33 connects the pivot pin 32 to a pin 18^a on the operating arm.

The rotary movement of the crank pin 28 will impart through the pitman 29, an oscillatory movement to the radius arm 30, and the said radius arm through the link 33, will impart an oscillatory movement to the pin 18^a and to the operating arm 18. It will be manifest from an inspection of Figs. 2 and 3, that on account of the fact that the operating arm 18 is shorter than the radius arm, the angle through which the operating arm 18 and pin 18^a are oscillated (indicated by the arc "a") is much greater than the angle through which the radius arm is oscillated (indicated by the arc "b").

In designing the parts comprising the gearing, and as more particularly indicated in the diagrammatic views shown in Figures 2 and 3, the angle "a" is approximately 130°, while the angle "b" is approximately 60°. An oscillation having an amplitude of 130°,—namely, 65° to one side of the vertical and 65° to the other side of the ver-

tical—is about that required of the cylinder 12 in a washing machine of the kind described. The lengths of the several parts may be given in terms of the crank arm, (namely, the arm "r" or radius of the circle "z" in which the crank pin 28 rotates) as a unit, substantially as follows:

The pitman 29 is of a length equal to four times the length of the crank arm; the radius arm is twice the length of the crank arm; the link 33 is $\frac{15}{16}$ of the length of the crank arm; and the operating arm 18 or the radius of the arcuate path of the pin 18^a, is $1\frac{1}{2}$ times the length of the crank arm. With the parts of this length, the radius arm is designed to have an amplitude of oscillation of approximately 60°.

As will be manifest, these proportions may be varied in many ways to suit the conditions and the requirements demanded of the particular gearing, and are only specified for purposes of illustration.

In locating the several centers, a line $x-x$ may be drawn through the center of the crank pin circle, to represent the median position of the pitman 29. The permitted length of the crank or the radius of the crank pin circle is then determined and after the circle of the crank pin 28 is described, the length of the pitman is laid out on the line $x-x$ to the right (as illustrated) from both sides of the crank pin circle, to give the points on said line indicating the limits of movement of its right hand end. The line $y-y$ is then drawn at right angles to the line $x-x$ through the point on the line $x-x$, midway between the said limits. With a point "s" on the line $y-y$ as a center, and a radius of proper length, the arc "a" is described,—this being the arc through which the pin 18^a on the operating arm is to oscillate. With a point "t" on the line $y-y$ as a center, and a longer radius the arc "b" is described, this representing the arc through which the pin 32 on the radius arm 30 is to oscillate. In the present example, the radius arm selected, as already pointed out, is twice the crank arm or the radius of the circle of the crank pin 28, and the position of its center on the line $y-y$ is such that the arc described about said center is approximately 60° between the points where it intersects the line $x-x$.

In Figs. 4 and 5, I have shown diagrammatically the relative positions of the several parts of the gearing for each 30° angle of movement of the crank from 0° to 360°. To save confusion, the positions of the parts from 0° to 180° are shown in Fig. 4, and the positions from 180° to 360° are shown in Fig. 5. The 0° position of the crank corresponds to the left-hand limit of movement of the pitman, while the 180° position of the crank corresponds to the right-hand limit of movement of the pit-

man. Fig. 4 thus represents the movement of the operating arm and of the radius arm away from the crank orbit, while Fig. 5 represents the movement of the operating 5 arm and of the radius arm towards the crank orbit.

It will be observed upon an examination of the said diagrams, that in the advance of the crank from 0° to 60° , the radius arm 10 and operating arm are nearly parallel, and, being linked together, their ends move approximately equal distances. From 60° to 90° this parallelism disappears, the angle between the two arms approaching a right 15 angle, so that the movement of the end of the operating arm is greatly increased as compared to the movement at the end of the radius arm, and this increased movement of the end of the operating arm is 20 maintained, but to a somewhat less extent, from 90° to 120° . At the 120° angle the radius arm and operating arm are moved at practically the same speed. From 120° to 150° the end of the operating arm does 25 not move as fast nor as far as the end of the radius arm,—this being due to the changing angle of the link. From 150° to 180° the slowing down of the end of the operating arm as compared to the movement 30 of the end of the radius arm, is still more apparent and is sufficient to off-set the crank irregularity so that the movements from 150° to 180° and from 180° to 210° , are no greater than from 330° to 360° and 35 from 0° to 30° . In fact, the parts are so designed as to make said movement a little less, in order to produce a better average between the movement from 270° to 300° , as compared to the movement from 90° to 220° . 40

The improved gearing has particular advantages when applied to a power driven washing machine of the kind herein described.

45 The relative slow stopping and starting of the oscillating cylinder type of washer, with an amplitude of oscillation of the cylinder of 130° or more, is desirable and important in that it gives the mass of clothes time to fall from one side of the cylinder to the other, when the movement of the cylinder is reversed.

The slower stopping and starting at both 55 ends of the oscillating movement of the operating arm is compensated for by a more rapid movement of said arm at the middle of the throw. This is of particular advantage in such a washing machine, since the clothes are forced through the water at a higher speed and with a more vigorous cleansing action.

60 This mechanical movement eliminates gearing, prevents backlash, lost motion, shock, noise, unnecessary wear and friction, and reduces the weight and momentum of

the moving parts, with the resultant reduction in breakage. It is simple, compact, easily assembled, and is economical in construction.

It will be noted that the crank is required 70 to rotate more than 90° in each direction to bring the operating arm to its middle position. This adds to the smoothness of operation, since the crank must overcome the inertia of the parts, in addition to friction 75 and other resistances, when moving from 0° to 90° , or from 180° to 270° . From 90° to 180° and from 270° to 360° the crank is only required to overcome the friction and other resistances minus the momentum of the moving parts. Hence the advantage of increasing the angle through which the crank moves up to mid-stroke of the operating arm in both directions.

These and other advantages of the new 85 mechanical movement will be apparent to those skilled in the art.

While in describing the invention, I have referred to details of construction and arrangement, the invention is in no way 90 intended to be limited thereto, except in so far as may be pointed out in the appended claims.

I claim as my invention:—

1. A gearing for washing machines comprising; an operated member capable of a rotary, oscillatory movement; a crank and pitman; means intermediate said pitman and said operated member adapted to oscillate the operated member at an accelerated 95 rate from the points of reversal to the mid point of the oscillatory movement, the rates of acceleration from each reversal point being substantially the same; and means for driving said crank. 100

2. A gearing for washing machines comprising; an operated member capable of a rotary, oscillatory movement; a crank and pitman; means intermediate said pitman and said operated member adapted to oscillate the operated member at a rapidly 110 accelerated rate from the points of reversal to the mid point of the oscillatory movement, the rates of acceleration from each reversal point being substantially the same, and the rates of movement approaching and leaving both points of reversal being equally 115 slow; and means for driving said crank.

3. A gearing for washing machines comprising; an operated member capable of a rotary, oscillatory movement; a rocker arm adapted for actuating said operated member; a pivoted radius arm; means connecting said radius arm and rocker arm; a crank and pitman connected to said radius arm; 120 said rocker arm and radius-arm-connecting-means being adapted, and said several parts being relatively proportioned and positioned, to oscillate the operated member at a rapidly accelerated rate from the points 125 130

of reversal to the mid point of the oscillatory movement, with the rates of acceleration from each reversal point substantially the same, and the rates of movement approaching and leaving both points of reversal, equally slow; and means for driving said crank.

4. A gearing for washing machines comprising; an operated member capable of a 10 rotary, oscillatory movement; a rocker arm adapted for actuating said operated member; a pivoted radius arm having a length greater than the length of said rocker arm; a link connecting said radius arm and 15 rocker arm; a crank and pitman connected with said radius arm; said parts being relatively proportioned and positioned to oscillate the operated member at a rapidly accelerated rate from the points of reversal 20 to the mid point of the oscillatory movement, the rates of acceleration from each reversal point being substantially the same, with the rates of movement approaching and leaving both points of reversal equally 25 slow; and means for driving the crank.

5. A gearing for washing machines com-

prising; an operated member capable of a rotary, oscillatory movement; a rocker arm adapted for actuating said operated member; a pivoted radius arm of a length 30 greater than the length of said rocker arm; a link connecting said radius arm and rocker arm; a crank and pitman connected with said radius arm; said pitman being relatively short and the radius arm, link, 35 and rocker arm being relatively proportioned and the pivoted point of the radius arm and rocker arm being positioned with reference to the crank arm center so that the link assumes a position substantially at 40 right angles to the pitman at the remote end of the stroke; and means for driving the crank.

In testimony that I claim the foregoing as my invention, I affix my signature in the 45 presence of two witnesses, this 27th day of April, A. D., 1920.

BRUCE CLARK WHITE.
